TRUNK LOCK

Oscar Lalonde, Bronx, N. Y.

Application January 21, 1941, Serial No. 375,303

15 Claims. (Cl. 70—75)

This invention relates to locks particularly adapted for use in connection with trunks or other equipment having hasps, keepers and locking means therefor.

In trunk locks it has heretofore been common to provide a lock which may be opened either by a key or by combination means. In this type of lock the locking means has usually been mounted on the trunk within the keeper plate and the combination means only has been mounted on the hasp. Such an arrangement does not lend itself well to employment of a standard key operated lock, and the use of a standard key operated lock in conjunction with the combination means is very desirable from the standpoint of availability as well as economy.

Moreover, mounting of the key operated lock mechanism on the trunk within the keeper plate and mounting of the locking means only on the hasp involves considerable installation trouble in attaining the proper co-operative action between the mechanism and the means because of inaccessibility of the key operated lock mechanism. Further, the keeper plate, with the key operated lock mechanism therein, and the hasp which carries the combination means, are both riveted to the trunk, and in the event of trouble in installation of the combination means in co-operative relation with the key operated lock mechanism, the keeper plate, or the hasp, or both, may have to be removed from the trunk after being riveted thereon, with resulting danger of damage to the trunk. This also applies if repairs are necessary.

Accordingly, the principal object of my invention is to provide a lock that may be operated either by a key or by combination means and which, by reason of mounting of both key operated lock mechanism and combination operated mechanism on a hasp, overcomes objections such as pointed out above.

Another object of my invention is to provide a trunk lock that may be opened either by a key or by combination means and which, due to mounting on both key operated lock mechanism and combination operated mechanism on a standard trunk hasp, enables the use of standard key operated trunk lock mechanism without requirement for additional installation space or undue projection of the lock from the trunk.

A further object of my invention is to provide a lock that may be opened either by a key or by combination means and which, by improvement in arrangement, construction and selective operation of key and combination controlled

parts, affords an extremely compact, efficient, and inexpensive unit for installation upon a hasp or any other type of equipment where the use of such a lock is desirable.

The invention consists of the construction, combination and arrangement of parts, as herein illustrated, described and claimed.

In the accompanying drawings, forming part hereof, is illustrated one form of embodiment of the invention, in which:

Figure 1 is a perspective view of a trunk lock embodying my invention and installed upon a hasp shown locked to a keeper plate;

Figure 2 is an enlarged transverse vertical sectional view on the lines 2—2 of Figure 1, looking in the direction indicated by the arrows;

Figure 3 is an enlarged transverse horizontal sectional view on lines 3—3 of Figure 1, looking in the direction indicated by the arrows;

Figures 4, 5 and 6 are isolated plan views on the lines 4—4, 5—5, and 6—6, respectively, of Figure 2, looking in the directions indicated by the arrows;

Figure 7 is an exploded detail perspective view of a connector, a trunk lock, and a casing therefor as shown in Figure 2;

Figure 8 is an exploded detail perspective view of combination disks, a control plate, and interposed washers shown in Figure 2; and,

Figure 9 is an exploded detail perspective view of a key plug, a disk carrying ring, and a casing cover, as shown in Figure 2.

Referring to the drawings, and more particularly to Figure 1, the numeral 10 indicates a front portion of a trunk and 11 indicates a similar portion of its lid. Secured to the front portion of the trunk, as by rivets 12, is a hasp plate 13 having a hinge 14 connecting a standard hasp 15 provided at the top and rear with a cup 16.

The trunk lid 11 has a keeper plate 18 having at the bottom a depression 19 for reception of the hasp 15 proper, and said plate also has above said depression 19 an arcuate recess 20 for reception of the cup 16 of said hasp. A circular opening 21 is formed in the keeper plate 18 centrally and within the recess 20, and when the lid 11 of the trunk is closed and the hasp 15 is swung into engagement with the keeper plate 18, bolts hereinafter described and which are mounted on the hasp 15, pass through the opening 21 and are engaged back of the edge to lock the trunk.

The keeper plate 18 is secured to the lid 11 of the trunk, as by rivets 22, which pass through openings in ears 23 formed on said plate and

bearing against the lid at opposite sides of the opening therein. Secured to the keeper plate 18 at the rear by rivets 24, is a plate 25 on the trunk lid 11 provided with a lock casing receiving cup 26. In accordance with my invention a lock, which may be opened either by a key or by combination means, is mounted on the hasp 15 and passes in and out of the keeper plate opening 21 and the cup 26 when the hasp 15 is swung toward and away from the keeper plate 18. Said lock is preferably mounted, constructed and operated as follows:

An annular lock casing 27 (Figures 2 to 7) is provided to house movable parts of the lock and said casing has in its side wall, diametrically opposed bolt openings 28. The casing 27 is further provided with cover plate lug receiving recesses 29 aligned with the bolt openings 28, and with diametrically opposed attaching lugs 30 spaced ninety degrees apart from the recesses 29.

Slidably mounted in the casing 27 to pass in and out of the bolt openings 28 are spaced, opposed lock bolts 31 formed integrally with a pair of lock bolt plates 32 slidably overlapping each other in said casing, each having aligned, spring receiving slots 33. Positioned in the slots 33 and bearing against lugs 34 on the plates 32 are small coil springs 35 which act to force the plates 32 and the bolts 31 outwardly in opposite directions so that said bolts normally project outwardly of the casing 27 through the bolt openings 28. The springs 35 and beveled faces 36 on the bolts 31 enable said bolts to snap past the circular edge of the keeper plate opening 21 when the hasp 15 is swung toward the same. Thereupon the bolts 31 through the action of the springs 35 engage the back of keeper plate 18 adjacent the opening 21 to lock the trunk.

The lock bolt plates 32 are provided centrally thereof with key lugs 37 and key spaces 38 (Figure 7) which, when the plates are assembled together, present a key opening 39 (Figure 4) disposed centrally of the lock. In accordance with my invention, the bolt plates 32 are provided with pins 40 forming part of a connection whereby the lock may be operated through the medium of means hereinafter described.

Arranged for partial rotation in the casing 27, and bearing against the lock bolt plates 32, is a substantially circular connector plate 41 (Figures 5 and 7) provided with a key opening 42 axially aligned with the key opening 39 of bolt plates 32. The connector plate 41 has diametrically opposed, substantially triangular shaped cam openings 43 in which extend the pins 40 of bolt plates 32. Pivotal mounted, as at 44, upon the connector plate 41 is a lever 45 which has at its free end a disk engaging lug 46. Secured to the opposite end of the lever 45 is a leaf spring 47 that extends between the side wall of the casing 27 and a lug 48 on the connector plate 41.

A key plug 49 (Figures 2 and 9) is provided axially with opposed inreaching slotted openings 50 which, when said plug is fitted in casing 27, are aligned with the key openings 39 and 42 of bolt plates 32 and connector plate 41, respectively. When opening the lock by a key inserted through the openings 50, 42 and 39 whereupon, by turning the key in the proper direction to engage the key lugs 37, the bolts 31 and plates 32 will be drawn inwardly toward each other so that the lock may be opened.

The key plug 49 is provided with an enlarged head 51 and a reduced shank 52. The shank 52 has rotatably fitted thereon a ring 53 having pe-

ripheral key ways 54 and 55. Mounted on the ring 53 is a lock casing cover plate 56 provided centrally with an opening 57 and lugs 57', 57'' which fit in the key ways 54 and 55 of said ring. 5 The cover plate 56 is provided with diametrically opposed lugs 58 for securing the plate 56 on the casing 27 in the recesses 29 thereof. The cover plate 56 bears against the head 51 of the key plug 49 and said key plug and the ring 53 carry lock 10 opening means preferably arranged and constructed as follows.

A washer 59 (Figures 2 and 8) is fitted on the ring 53 back of the cover plate 56 and has a lug 59' engaged in the key way 54 of the ring. Bearing 15 against said washer and rotatably mounted on the ring 53 is a disk 60 provided centrally with an opening 61 through which the ring 53 extends. This disk 60 has an arcuate slot 62 and a peripheral notch 63. A washer 64 is mounted on the ring 53 and has a lug 64' fitted in the key way 54 of said ring. The washer 64 bears against the disk 60 at the side opposite that bearing against the washer 59.

Rotatably mounted on the ring 53 and bearing 25 against the washer 64 is a disk 65 provided centrally with an opening 66 through which the ring 53 extends. Secured to the disk 65 is a lug 67 which extends into the slot 62 of the disk 60 for interengagement therewith. The disk 65 also has a lug 68 extending in a direction opposite that of the lug 67 and having a function to be presently described. The disk 65 has a peripheral notch 69, and mounted on the ring 53 and bearing against said disk is a washer 70 having a lug 70' fitted in the key way 54 of said ring.

Rotatably mounted on the ring 53 and bearing 35 against the washer 70 is a disk 71 provided centrally with an opening 72 through which the ring 53 extends. The disk 71 contains diametrically opposed arcuate slots 73 and 74 and a peripheral notch 75. The lug 68 of disk 65 extends through slot 73 of disk 71 for interengagement therewith, and mounted on the ring 53 at the side of the disk 71 opposite that bearing against the washer 45 70 is a washer 76 having a lug 76' fitted in the key way 54 of said ring.

The key plug 49 has fixed thereon and bearing 50 against the washer 76 control means comprised of a plate 77 having a square sided opening 78 in which fits a square sided reduced end portion 79 of the key plug shank 52. On the control plate 77 is a lug 80 which extends in the slot 74 of disk 71 for interengagement therewith. The control plate 77 has in its periphery a cam 55 81 having a shoulder 82. The shoulder 82 is adapted for engagement with, and disengagement from, a detent 83 (Figure 5) formed on the lever 45.

The key plug 49 and described parts carried 60 thereby constitute a unit which is associated with the described parts in the casing 27 and secured therewith on the hasp 15 in the cup 16. Accordingly, the several disks 60, 65, 71, and the key plug 49 and control plate 77 are rotated relatively 65 to align notches 63, 69, 75, the cam 81 and the shoulder 82 with each other. Thereupon, the key plug and combination unit is placed in the casing 27, so that the detent 83 of the pivoted lever 45 enters the space between the cam 81 and the shoulder 82 of the control plate 77, and the disk engaging lug 46 of the lever 45 enters the notches 63, 69, 75 of the disks. Under these conditions, the lugs 58 of cover plate 56 will be aligned with the recesses 29 in the casing 27 so that upon pressing the lugs in said recesses, the

cover plate 56 is secured on the casing 27 over the parts therein and with the key plug projecting outwardly of the cover plate through the opening 51.

The casing 27 and parts therein are now placed in the cup 16 of the hasp 15 so that the front end of the key plug 49 projects forwardly of the hasp through an opening 84 (Figure 2) formed in the hasp cup 16 centrally thereof. At the same time, the lugs 30 of the casing 27 are secured in openings 85 (Figure 3) formed in the hasp cup at opposite sides of the opening 84, and the lock is thus securely fastened to the hasp.

The key plug 49 has in its front at opposite sides of the key openings 50, threaded openings 86 for the reception of small screws 87 which serve to secure a circular dial 88 to said key plug and pass through openings formed in said dial. The dial 88 is thus disposed forwardly of the hasp 15 over a rounded portion of the cup 16 so as to be rotated to set or unset the disks 60, 65, 71, as hereinafter described.

The dial 88 contains key slots 89 aligned with the key slots 50 of the plug 49 and with the key openings 39 and 42 of the bolt plates 32 and the connector plate 41, respectively. The dial 88 has an annular beveled portion 90 provided there-around with a scale including the usual graduated marks and numbers herein shown as comprising the series 0 to 9, inclusive. Through rotation of the dial 88 predetermined numbers of this series are successively brought opposite a mark 91 on the keeper plate 18 to set the disks 60, 65 and 71 so that the lock may be opened by the dial.

In the operation of the lock, and opening by a key, the hasp will be closed as shown in Figures 1 to 3, inclusive and the bolts 31 will be engaged with the keeper plate 18 at the rear. The key is inserted through the openings 89, 50, 42 and 39 of the dial 88, key plug 49, connector plate 41, and bolt plates 32, respectively, whereupon by turning the key in the proper direction it engages the lugs 37 of the bolt plates 32, thus drawing said plates and the bolts 31 inwardly against the said plates and bolt expanding action of the springs 35, and disengaging the bolts from the keeper plate 18. The lock now being opened, the hasp 15 may then be swung forwardly at which time the lock passes out of the cup 26 through the opening 21 of the keeper plate 18, and the lid 11 of the trunk 10 can thereafter be raised to open the trunk.

Assuming now that the lid of the trunk has been closed, that the hasp is also closed as shown in Figures 1 to 3, and that it is desired to open the lock by the dial 88 instead of the key. The disks 60, 65, 71, being at this time unset, it is necessary to set them, which is accomplished by rotating the dial 88 to successively bring three of a predetermined combination of the numbers thereon opposite the mark 91 on the keeper plate 18. Accordingly, the dial 88 is turned to the left or counter-clockwise as viewed in Figure 1, to bring the first of the three numbers of the combination opposite the mark 91, whereupon the dial is turned to the right or clockwise to bring the second of the three numbers opposite the mark 91, after which said dial is again turned to the left or counter-clockwise to bring the third of said numbers opposite said mark.

This, through rotation of the key plug 49 and the control plate 71 by the dial 88, and interengagement of said plate and the disks 71, 65, 60, through the medium of the lugs 80, 68, 67, in the slots 74, 73, 62, respectively, rotates said disks so

that their notches 15, 69, 63, are brought into alignment. Thereafter the dial 88 is turned to the right or clockwise, rotating the key plug 49 and the control plate 71 in the same direction until the shoulder 82 and the cam 81 of said control plate are brought into alignment with the notches 75, 69, 63, and opposite the detent 83 of the lever 45. The spring 47 then causes pivotal movement of the lever 45 so that its detent 83 swings inwardly of the shoulder 82 on the control plate 71 and the lug 46 enters the aligned notches 75, 69, 63 of the disks 71, 65, 60, respectively.

Thereupon, through further rotation of the dial 88 clockwise or to the right, the key plug 49, control plate 71 and disks 71, 65, 60, are likewise rotated, causing the shoulder 82 and the detent 83 engaged therewith to rotate the connector plate 41 so that the cam edges of its openings 43 engage the pins 40 of the bolt plates 32 and slide said bolt plates and the bolts 31 inwardly toward each other against the bolt and plate expanding action of the springs 35. The bolts 31 are thus disengaged from the keeper plate 18, the lock is opened, and the hasp 15 may then be swung outwardly, at which time the lock passes out of the cup 26 through the keeper plate opening 21.

When the hasp 15 has been swung outwardly, the dial 88 is turned to the left or counter-clockwise. This causes corresponding movement of the key plug 49 and the control plate 71 so that the cam 81 on the control plate forces the detent 83 with pivotal movement of the lever 45 outwardly and the detent 83 is disengaged from the shoulder 82 of the control plate. At the same time, and through this action of the cam 81, the lug 46 of the lever 45 is disengaged from the notches 75, 69, 63 of the disks 71, 65, 60, respectively, and swings outwardly beyond the latter. By further turning of the dial 88 counter-clockwise or to the left, the key plug 49 and the control plate 71 receive corresponding movement so that through interengagement of the lugs 80, 67, 68 with the disks 71, 65, 60, respectively, said disks are rotated, the combination is unset, and the notches 15, 69 and 63 are moved out of alignment.

The lug 46 of the lever 45 is thus, through unsetting rotation of the disks, engaged with unnotched edge portions thereof and the connection between the control plate 71 and the connector plate 41 is broken. When said connection is broken, the springs 35 force the bolt plates 32 and the bolts 31 outwardly, with accompanying partial rotation of the connector plate 41 due to riding of the pins 40 along the cam edges of the openings 43 to the outer ends thereof. With the hasp 15 swung forwardly, the lid 10 of the trunk 10 may be opened, and when said lid is closed and the hasp 15 is swung rearwardly into engagement with the keeper plate 18, the bolts 31 are engaged back of said plate and the lock enters and is positioned in the cup 26 of the plate 25. Thereupon the lock may be opened either by the key or by the dial, as previously described.

A key operated lock of standard construction may, in accordance with my invention, be employed in conjunction with combination means on a hasp, through the novel arrangement and construction of the parts and connections comprising said invention, and while the use of a standard key operated lock is contemplated and, with the exception of the pins 40, is in all substantial respects disclosed in conjunction with the form of embodiment of my invention herein illustrated and described, it is to be expressly

understood that my invention is not limited to such a lock or said form of embodiment or otherwise than by the terms of the appended claims.

Having thus fully described the invention, what is claimed as new and desired to be secured by United States Letters Patent is:

1. In a lock having a keeper and a hasp hinged for swinging movement relative thereto, the combination of a lock having a key operated opening plug mounted on the hasp, said lock being disposed rearwardly of the hasp for co-operation with the keeper and said plug being rotatably disposed in an opening extending through said hasp, interengageable combination disks rotatably mounted on the key plug, control means interengageable with one of said disks and fixed on the key plug, a dial fixed on the key plug forwardly of the hasp and operable to rotate the plug and the control means thereby to set and unset the disks, and mechanism actuated by the control means for connecting the lock therewith when the disks are set and for disconnecting the lock from said control means when said combination disks are unset.
2. In a lock having a keeper and a hasp hinged for swinging movement relative thereto, the combination of a lock and a key operated opening plug therefor both mounted on the hasp, said lock being disposed rearwardly of the hasp for co-operation with the keeper and said plug being rotatably disposed in an opening extending through said hasp, interengageable combination disks rotatably mounted on the key plug, control means interengageable with one of said disks and fixed on the key plug, a dial fixed on the key plug forwardly of the hasp and operable to rotate the plug and the control means to set and unset said disks, and mechanism enabling the lock to be operated either by the dial or a key, said mechanism comprising a device actuated by the control means for connecting the lock therewith when the combination disks are set, and means on the control means for disconnecting said device therefrom when said disks are unset.
3. In a lock having a keeper and a hasp hinged for swinging movement relative thereto, the combination of a lock and a key operated opening plug therefor both mounted on the hasp, said lock being disposed rearwardly of the hasp for co-operation with the keeper and said plug being rotatably disposed in an opening extending through said hasp, interengageable combination disks rotatably mounted on the key plug, control means interengageable with one of said disks and fixed on the key plug, a dial fixed on the key plug forwardly of the hasp and operable to rotate the plug and the control means to set and unset said disks, and mechanism controlled by said control means enabling the lock to be operated either by the dial or a key, said mechanism comprising a plate rotatably mounted between the control means and the lock and connected with the latter, a detent pivotally mounted on the plate and connecting it with the control means when said disks are set, and a cam on the control means for disconnecting said detent from the control means when the combination disks are unset.
4. In a lock having a keeper and a hasp pivoted for swinging movement relative thereto, the combination of a lock and a key operated opening plug therefor both mounted on the hasp, said lock being disposed rearwardly of the hasp for co-operation with the keeper and said plug being rotatably disposed in an opening extending
5. In a lock having a keeper and a hasp rotatably mounted on the key plug, control means interengageable with one of said disks and fixed on the key plug forwardly of the hasp and operable to rotate the plug and the control means to set and unset said disks, and mechanism controlled by the control means enabling the lock to be operated either by the dial or a key, said mechanism comprising a plate rotatably mounted between the lock and said disks, a spring controlled detent pivotally mounted on the plate and connecting it with the control means when said disks are set, pin and cam connections between the plate and the lock, and a cam on the control means for disconnecting said detent therefrom when the combination disks are unset.
- 20 6. In a lock having a keeper and a hasp pivoted for swinging movement relative thereto, the combination of a lock and a key operated opening plug therefor both mounted on the hasp, said lock being disposed rearwardly of the hasp for co-operation with the keeper and said plug being rotatably disposed in an opening extending through said hasp, interengageable combination disks rotatably mounted on the key plug, a control plate fixed on the key plug and interengageable with one of said disks, said control plate having a shoulder in the periphery thereof, a dial fixed on the key plug and operable to rotate the plug and the control plate to set and unset said disks, and mechanism enabling the lock to be operated either by the dial or a key, said mechanism comprising a connector plate rotatably mounted between the lock and the control plate, said connector plate having a central opening for passage of the key to the lock and diametrically opposed cam shaped openings, pins on the lock extending in the cam shaped openings of the connector plate, a spring controlled detent pivotally mounted on the connector plate and engaged with the shoulder of the control plate when said disks are set, and a cam on the control plate for disconnecting the spring controlled detent therefrom when the combination disks are unset.
- 25 7. In combination with a pair of opposed spring actuating lock bolts, a key plug through which a key may be inserted to rotate the plug and unlock the bolts, and combination means mounted on the key plug, of a dial fixed on the key plug to rotate it and set said means, a plate between said means and the bolts, bolt unlocking connection between the plate and the bolts, and a device on the plate for connecting it with the key plug when said means is set, to thereby unlock the bolts with said dial.
- 30 8. In combination with a lock having a pair of opposed spring impelled bolts, a key plug through which a key may be inserted to rotate the plug and unlock the bolts, and combination disks mounted on the key plug, of a dial fixed on the key plug to rotate it thereby to set and unset said disks, a plate between the permutation means and the bolts, bolt unlocking connection between the plate and the bolts, a device on the plate for connecting it with the key plug when said disks are set, whereby to unlock the bolts with said dial, and means for disconnecting said device from the key plug when said disks are unset, whereby to unlock the bolt with a key instead of with the dial.
- 35 9. The combination with a lock bolt, a key plug through which a key may be inserted to rotate the plug and unlock the bolt, and combination
- 40 10. The combination with a lock having a pair of opposed spring actuating lock bolts, a key plug through which a key may be inserted to rotate the plug and unlock the bolts, and combination disks mounted on the key plug, of a dial fixed on the key plug to rotate it and set said means, a plate between said means and the bolts, bolt unlocking connection between the plate and the bolts, and a device on the plate for connecting it with the key plug when said means is set, to thereby unlock the bolts with said dial.
- 45 11. The combination with a lock having a pair of opposed spring impelled bolts, a key plug through which a key may be inserted to rotate the plug and unlock the bolts, and combination disks mounted on the key plug, of a dial fixed on the key plug to rotate it thereby to set and unset said disks, a plate between the permutation means and the bolts, bolt unlocking connection between the plate and the bolts, a device on the plate for connecting it with the key plug when said disks are set, whereby to unlock the bolts with a key instead of with the dial.
- 50 12. The combination with a lock bolt, a key plug through which a key may be inserted to rotate the plug and unlock the bolt, and combination
- 55 13. The combination with a lock having a pair of opposed spring actuating lock bolts, a key plug through which a key may be inserted to rotate the plug and unlock the bolts, and combination disks mounted on the key plug, of a dial fixed on the key plug to rotate it and set said means, a plate between said means and the bolts, bolt unlocking connection between the plate and the bolts, and a device on the plate for connecting it with the key plug when said means is set, to thereby unlock the bolts with said dial.
- 60 14. The combination with a lock having a pair of opposed spring impelled bolts, a key plug through which a key may be inserted to rotate the plug and unlock the bolts, and combination disks mounted on the key plug, of a dial fixed on the key plug to rotate it thereby to set and unset said disks, a plate between the permutation means and the bolts, bolt unlocking connection between the plate and the bolts, a device on the plate for connecting it with the key plug when said disks are set, whereby to unlock the bolts with a key instead of with the dial.
- 65 15. The combination with a lock bolt, a key plug through which a key may be inserted to rotate the plug and unlock the bolt, and combination
- 70 16. The combination with a lock having a pair of opposed spring actuating lock bolts, a key plug through which a key may be inserted to rotate the plug and unlock the bolts, and combination disks mounted on the key plug, of a dial fixed on the key plug to rotate it and set said means, a plate between said means and the bolts, bolt unlocking connection between the plate and the bolts, and a device on the plate for connecting it with the key plug when said means is set, to thereby unlock the bolts with a key instead of with the dial.
- 75 17. The combination with a lock having a pair of opposed spring impelled bolts, a key plug through which a key may be inserted to rotate the plug and unlock the bolts, and combination disks mounted on the key plug, of a dial fixed on the key plug to rotate it thereby to set and unset said disks, a plate between the permutation means and the bolts, bolt unlocking connection between the plate and the bolts, a device on the plate for connecting it with the key plug when said disks are set, whereby to unlock the bolts with a key instead of with the dial.

disk means mounted on the key plug, of a dial fixed on the key plug to rotate it and set said means, a plate between said means and the bolt, a bolt unlocking connection between the plate and the bolt, said connection comprising a cam on the plate and a pin on the bolt adapted to be engaged by said cam, and a spring controlled detent on the plate for connecting it with the key plug when said means are set, whereby to unlock the bolt with said dial instead of with a key.

9. The combination with a lock bolt, a key plug through which a key may be inserted to rotate the plug and unlock the bolt, and combination disk means mounted on the key plug, of a dial fixed on the key plug to rotate it and set and unset said means, a connector plate between said means and the bolt, a bolt unlocking connection between the connector plate and the bolt, said connection comprising a cam on the connector plate and a pin on the bolt adapted to be engaged by said cam, a control plate fixed on the key plug and provided with a shoulder, a spring controlled detent on the connector plate for engaging the shoulder of the control plate when said means are set, whereby to unlock the bolt with said dial instead of with the key, and means on the control plate for disengaging said detent from said shoulder when said disk means are unset, whereby to unlock the bolt with a key instead of with said dial.

10. The combination with a lock bolt, a key plug through which a key may be inserted to rotate the plug and unlock the bolt, and combination means mounted on the key plug and having notches brought into and out of alignment when said means is set and unset respectively, of a dial fixed on the key plug to rotate it and set or unset said means, a connector plate between said means and the bolt, said connector plate having a key opening and a cam shaped opening, a bolt unlocking connection between the connector plate and the bolt, said connection comprising a pin on the bolt extending in the cam shaped opening of the connector plate, a control plate fixed on the key plug and provided with a shoulder, a spring controlled lever pivotally mounted on the connector plate and having a detent and a lug for engaging the shoulder and notches respectively of the control plate and combination means when the latter is set, whereby to unlock the bolt with the dial instead of with said key, and a cam on the control plate for disengaging said detent and lug from said shoulder and notches when said combination means is unset, whereby to unlock the bolt with the key instead of with said dial.

11. The combination with a pair of opposed spaced slideable spring projected bolts, a key plug aligned with the space between the bolts and through which a key may be inserted to rotate the plug and retract the bolts, and combination means mounted on the key plug, of a dial fixed on the key plug to rotate it and set the combination means, a plate rotatably mounted between the bolts and the key plug and having a key opening opposite the same for passage of the key between said bolts, bolt retracting connections between the plate and the bolts and disposed diametrically of the plate at opposite sides of its key opening, and means on the plate for connecting it with the key plug when the combination means is set, whereby to retract the bolts with said dial instead of with a key.

12. The combination with opposed spaced slideable spring locked bolts, a key plug aligned with

the space between the bolts and through which a key may be inserted to rotate the plug and unlock the bolts, and combination means mounted on the key plug, of a dial fixed on the key plug to rotate it and set or unset the combination means, a plate rotatably mounted between the bolts and the key plug and having a key opening opposite the same for passage of a key between said bolts, bolt unlocking connections between the plate and the bolts and disposed diametrically of the plate at opposite sides of its key opening, a device on the plate for connecting it with the key plug when the combination means is set, whereby to unlock the bolts with the dial instead of with a key, and means for disconnecting said device from the key plug when the combination means is unset, whereby to unlock the bolts with the key instead of with said dial.

13. The combination with opposed spaced slideable spring locked bolts, a key plug aligned with the space between the bolts and through which a key may be inserted to rotate the plug and unlock the bolts, and combination means mounted on the key plug, of a dial fixed on the key plug to rotate it and set the combination means, a connector plate rotatably mounted between the bolts and the key plug and having a key opening opposite the same for passage of the key between said bolts, said connector plate having diametrically opposed cam shaped openings formed therein at opposite sides of its key opening, bolt unlocking connections between the connector plate and the bolts and disposed diametrically of the connector plate at opposite sides of its key opening, said connections comprising pins on the bolts extending in the cam shaped openings of the connector plate, a control plate fixed on the key plug, and a device on the connector plate for connecting it with the control plate when the combination means is set, whereby to unlock the bolts with said dial instead of with a key.

14. The combination with opposed spaced slideable spring locked bolts, a key plug aligned with the space between the bolts and through which a key may be inserted to rotate the plug and unlock the bolts, and combination means mounted on the key plug, of a dial fixed on the key plug to rotate it and set or unset the combination means, a connector plate rotatably mounted between the bolts and the key plug and having a key opening opposite the same for passage of the plug between said bolts, said connector plate having diametrically opposed cam shaped openings formed therein at opposite sides of its key opening, bolt unlocking connections between the connector plate and the bolts and disposed diametrically of the connector plate at opposite sides of its key opening, said connections comprising pins on the bolts extending in the cam shaped openings of the connector plate, a control plate fixed on the key plug and provided with a shoulder, a spring controlled detent pivotally mounted on the connector plate for engaging the shoulder of the control plate when the combination means is set, whereby to unlock the bolts with the dial instead of with a key, and a cam on the control plate for disconnecting said detent from said shoulder when the combination means is unset, whereby to unlock said bolts with a key instead of with said dial.

15. In a lock having a casing provided with spaced openings, opposed spaced bolts in the casing spring locked through said openings, and a key plug extending in the casing toward the space between the bolts and through which a

key may be inserted to rotate the plug and unlock the bolts, the combination of interengageable combination disks rotatably mounted on the key plug and having peripheral notches, a notched control plate fixed on the key plug interengageable with one of said disks and having a peripheral shoulder, a dial fixed on said key plug for rotating same and the control plate to set or unset the combination disks and align or disalign their notches and the shoulder of the control plate, a connector plate rotatably mounted in the casing between the bolts and the control plate and having a key opening opposite the plug and the space between the bolts, said connector plate also having cam shaped openings formed therein at opposite sides of the key opening, pins on the bolts extending in the cam shaped

openings of the connector plate, a lever pivoted on the connector plate and having a detent and a lug for engaging the shoulder and notches of the control plate and the combination disks respectively, when the disks are set and the shoulder and notches are aligned, whereby the bolts may be unlocked by rotation of the dial instead of with a key, a leaf spring on the lever engaging the casing and causing the detent to bear against the edges of the combination disks, and a cam on the control plate for disengaging the detent and lug from the control plate shoulder and disk notches respectively when the disks are unset and said shoulder and notches are disaligned, whereby to unlock the bolts with a key instead of by rotation of said dial.

OSCAR LALONDE.
